UNITED STATES PATENT OFFICE.

WILBUR B. TIMBERLAKE, OF JACKSON, MICHIGAN.

EGG-TESTER.

1,221,629.

Specification of Letters Patent.

Patented Apr. 3, 1917.

Application filed July 16, 1914. Serial No. 851,340.

To all whom it may concern:

Be it known that I, WILBUR B. TIMBERLAKE, a citizen of the United States, residing at Jackson, in the county of Jackson and 5 State of Michigan, have invented certain new and useful Improvements in Egg-Testers, of which the following is a specification.

My invention relates to egg testing devices, particularly of the self-contained type in which an electric lamp, a battery for supplying electric current thereto, and suitable circuit-completing connections and conductors are employed, these all being mounted 15 within a case.

In the drawings—

Figure 1 is a plan view of a device embodying my invention;

Fig. 2 is a longitudinal section thereof 20 taken on the line II—II of Fig. 1;

Fig. 3 is a transverse sectional view taken on the line III—III of Fig. 2;

Fig. 4 is a longitudinal sectional view of a device embodying another form of my invention;

Fig. 5 is a sectional view on the line V—V of Fig. 4; and

Fig. 6 is a diagrammatic view illustrating the adaptation of the invention to a large 30 egg testing apparatus.

Fig. 7 is a plan view of an arrangement that I prefer to use in a device employing two lamps.

Fig. 8 is a central horizontal section of the 35 arrangement shown in Fig. 7.

Referring particularly to Figs. 1, 2 and 3, 2 indicates a box or casing, one side of which may be opened, being preferably hinged, as indicated at 3, in order to permit ready access to the interior. A partition 4 is employed to divide the interior of the casing into two compartments, in one of which is mounted a battery 5 constituting the source of electric supply. In the other compartment 45 is mounted an electric lamp 6 surrounded by a reflector 7, into the screw-threaded socket of which the stem or plug of the lamp is screwed in a well-known manner.

One of the terminals of the filament of the lamp connects with the reflector, which is of metal, and the other with the exposed plug contact 8.

9 and 10 designate respectively strips of 55 spring metal supported by the partition 4 and extending into the compartment in which is arranged the battery 5, with the

terminals of which they engage when the battery is in place. 11 indicates an elastic, spring arm secured to the metal plate 10 with which it has good electric connection. 60 The end of this arm is preferably formed into a loop 12 into which the reflector 7 is set and with which it is secured in such manner as to form a good electrical connection between the two. The loop end of the 65 arm 11, and the reflector and lamp which it carries, are arranged directly below an opening, 13, in one of the sides of the casing 2. A flexible sheet, curtain or cover 14, preferably of opaque fabric and constituting a 70 curtain of relatively soft material, extends over the opening 13, being secured to the side of the casing. I prefer to secure this fabric to the inner face of the side of the casing, although it might be secured on the outside, as represented in Fig. 4. An opening 75 is formed in the flexible cover 14 opposite the opening 13 and preferably of somewhat smaller size. The elasticity of the spring arm 11 holds the edge of the reflector in 80 close engagement with the flexible cover 14, directly behind the opening therein. The contact plate 9 is extended so as to be directly below or opposite to the terminal 8 of the lamp, so that by pressing the reflector and lamp inward a little, contact is 85 made between the terminal 8 and the plate 9, with the result that the electric circuit is completed and the lamp becomes illuminated. The tension of the spring is such 90 that it will ordinarily yield sufficiently, when an egg is placed upon the flexible cover 14 over the opening therein and resting upon the edge of the reflector, to cause a good contact to be made between the terminal 8 and the plate. The lighting of the lamp will then cause the egg to be illuminated so that its condition can be determined. The flexible cover or septum 14 95 serves as a light screen, and thus operates to assist in securing a good illumination of the egg.

I wish it to be understood that my invention is not limited in its useful applications to all of the features and details of arrangement which I have described and which are illustrated in Figs. 1, 2 and 3 of the drawings hereof. Thus in Figs. 4 and 5 I have illustrated a different embodiment of the invention. Here the lamp and reflector are supported stationarily, being mounted in an insulating socket 17. One of the conducting 100

wires, 19, from the battery leads directly to one of the terminals of the lamp, while the other, 20, is preferably secured to an elastic arm 11^a. This arm terminates in a loop, 12^a, that extends into the aperture 13 in the casing wall and bears against the flexible cover 14, which in this instance is secured to the outside of the casing and extends across the opening 13. This cover is flexible, and, as already described, preferably consists of a piece of opaque fabric perforated to correspond with the opening 13, and against the inner face of it the loop 12^a of the spring arm 11^a bears. This arm passes across a stationary contact piece or bridge 16, which is connected, by a wire 15, with the second terminal of the lamp. With the parts arranged as shown, if an egg be laid upon the flexible cover 14 over the opening therein, its weight will operate to move the arm 11^a sufficiently to close the circuit at the point where the said arm crosses the bridge 16, whereupon the lamp will be lighted and the egg illuminated.

In both forms of the invention which I have described, the electric circuit is normally open and is only closed when an egg is placed in position for testing. If, however, it should be desirable to maintain a steady illumination for a considerable period, this may be accomplished by means of a manually controlled circuit closer 18. This consists of a part arranged to be moved so as to bear upon the spring arm 11^a and force it into engagement with the bridge piece 16 where it is held until the manually controlled device 18 is again moved.

In Fig. 6 I have diagrammatically illustrated an egg testing apparatus of large capacity, adapted for testing a number of eggs at one and the same time. Here a number of lamps are shown connected in series, each being opposite an opening to receive an egg, like that in the flexible cover 14. In this arrangement of my invention a single circuit closer only may be employed, as represented in full lines, this being provided by a spring arm 11^a carrying an egg-supporting loop 12^a, and a bridge piece with which the said arm engages when depressed by the weight of an egg; or a plurality of circuit closers may be arranged in parallel, as indicated by dotted lines in said Fig. 6.

It will be seen that the piece of fabric 14 arranged as shown and described, constitutes a flexible, light-intercepting, perforated septum, upon which the egg is adapted to rest when placed for testing; and that the circuit closer of the electric system bears against the said septum and is arranged to be moved when the egg is placed over the opening in such septum. The circuit closer, as has been described, at its free end is shaped to support and more or less closely conform to an egg which it serves to sustain while being

illuminated for testing, it being understood that the edge of the reflector to which the flexible spring arm 11 may be secured, as represented in Figs. 1, 2 and 3, becomes part of the circuit closer and also a support for the egg when the arrangement is such as illustrated in those figures.

In Figs. 7 and 8 I have illustrated an embodiment of the invention possessing many of the features of the device illustrated in Figs. 1, 2 and 3, but differing therefrom in detail, and especially devised for use in a device employing two lamps. In these views a stationary conducting plate 9^b is secured to the partition 4, this being connected with the battery by a wire 20. The lamps and their reflectors are supported by the arms of a spring plate 11^b that serves as a conducting member of the circuit and is connected with the source of current by a wire 10^b. The plate 11^b is supported above the plate 9^b and parallel therewith and is secured in place by screws 21 which pass into the partition 4. An insulating piece 22 is interposed between the plates 9^b and 11^b. It will be understood that in the arrangement shown in these views the lamps and their reflectors are arranged below openings in the casing, and a flexible perforated light-intercepting septum 14 is arranged over each.

What I claim is:—

1. In an egg testing device, the combination of an inclosing casing in one wall of which is an opening, a flexible, yielding, light-excluding septum extending across the said opening, in which is a hole over which an egg may be placed, an electric illuminator within the casing opposite the said hole in the septum, and yielding circuit-closing means for the circuit of the illuminator, bearing against the said septum and arranged to be moved to close the circuit when an egg is placed against the septum.

2. In an egg testing device, the combination of a casing in one wall of which is an opening, a flexible yielding perforated septum extending across the said opening in the casing, an electric illuminator within the casing, yielding circuit closing means for controlling the circuit of the illuminator, and movable independently of the casing, such circuit closing means bearing against the septum so as to be moved therewith to close the circuit when an egg is put in position to be tested.

3. The combination of an inclosing casing, an electric lamp therein, the wall of the casing being perforated opposite the lamp, an open electric circuit including a source of electric supply and the said lamp, a circuit closer for the said circuit comprising a flexible arm freely movable independently of the casing and carrying a loop substantially concentric with the said opening in the wall of the casing the loop being shaped

- to receive an egg that is to be tested and arranged to be moved to close the circuit when an egg is placed for testing.
4. In an egg testing device, the combination of a casing, one wall of which is perforated, an electric lamp and surrounding reflector arranged in the said opening, an elastic arm constituting a part of the electric circuit of the lamp and supporting it and the reflector, such arm being arranged to yield when an egg is placed in position for testing, and a contact plate constituting another part of the electric circuit arranged to be engaged by one of the terminals of the lamp when it and the reflector are moved on an egg being put in position for testing.
5. In an egg testing device, the combination of a casing, one wall of which is perforated, an opaque, perforated, flexible cover placed across the said opening, an electric lamp and surrounding reflector arranged inside the said cover with the edge of the reflector resting against it, a source of electric supply supported within the casing, an elastic arm secured to and supporting the said reflector and lamp and holding it against the cover, the arm being connected with one terminal of the source of electric supply, and a contact plate arranged opposite the lamp with which one terminal thereof engages when the lamp and reflector are moved inwardly, the said contact plate being connected with the other terminal of the source of electric supply.
6. In an egg tester, the combination with an electric light, of a pliable sheet in advance of and mounted to yield inwardly toward the same, said sheet having an egg receiving opening, and a circuit closer operable upon inward movement of said sheet to complete the circuit of the light.
7. In an egg tester, the combination with a wall having an opening, and an electric light in rear of the opening, of a pliable sheet secured over said opening to yield inwardly toward the light, said sheet having an egg receiving opening, and a circuit closer operable by inward movement of said sheet to complete the circuit of the light.
8. In an egg tester, the combination with a wall having an opening and an electric light in rear of the opening, of a flexible sheet disposed over said opening and secured to the wall, the central portion of said sheet being free to move inwardly toward the light and having an egg receiving opening, and a circuit closer operable upon inward movement of said sheet to complete the circuit of the light.
9. An egg tester provided with an electric light-giving element, and a curtain of relatively soft flexible material with an opening therethrough for the reception of a portion of an egg, the tester being provided with electric contacts, one of which is under the control of the curtain and out of the path of an egg introduced into the egg-receiving hole of the curtain.
